UNITED STATES PATENT OFFICE

93,787

DESIGN FOR A BOTTLE

Julian R. Orton, Cincinnati, and Edwin W. Fuerst, Toledo, Ohio, assignors to The Tom Collins Corporation, Cincinnati, Ohio, a corporation of Ohio

Application August 13, 1934, Serial No. 52,944

Term of patent 7 years

To all whom it may concern:

Be it known that we, JULIAN R. ORTON and EDWIN W. FUERST, citizens of the United States of America, and residents of Cincinnati, Hamilton County, Ohio, and Toledo, Lucas County, Ohio, respectively, have invented a new, original, and ornamental Design for a Bottle, of which the following is a specification, reference being made to the accompanying drawing, forming a part thereof.

Fig. 1 is a perspective view of the bottle embodying the new design.

Fig. 2 is a top plan view of the bottle illustrated in Fig. 1.

We claim:

The ornamental design for a bottle, as shown.

JULIAN R. ORTON.
EDWIN W. FUERST.
